UNITED STATES PATENT OFFICE

CHARLES COURTLAND MCBURNEY, OF MARYSVILLE, KANSAS

WALL-PAPER-HANGING APPARATUS

Application filed May 31, 1928. Serial No. 281,708.

The present invention relates to improvements in wall paper hanging devices, and has reference more particularly to a hand operated apparatus for unrolling the wall paper from a roll, coating the same with paste on one side, brushing the coated strip against the wall or ceiling, and cutting the strip at the desired length.

Another important object of the invention is to provide a wall paper hanging apparatus of the above mentioned character wherein the container for the paste has connection with an air pump whereby to create a pressure in the container to effect the delivery of the paste to the distributor over which the strip of paper travels while being unrolled.

A further object is to provide a wall paper hanging apparatus that will save considerable time and labor in papering a wall or ceiling, the simplicity of my apparatus enabling the parts to be readily and easily operated.

A further object is to provide a wall paper hanging apparatus of the above mentioned character which is simple in construction, inexpensive, strong and durable and further well adapted to the purpose for which it is designed.

Other objects and advantages of the invention will become apparent from the following description when taken in connection with the accompanying drawings.

In the accompanying drawings wherein like reference characters indicate corresponding parts throughout the views:

Figure 1 is a side elevation of the wall paper hanging apparatus embodying my invention.

Figure 2 is an enlarged front elevation of the frame and the paste distributor showing the actuating means for the pivoted cutter and also illustrating the manner in which the brush is mounted on the frame.

Figure 3 is a vertical sectional view through the device showing the manner in which the wall paper is disposed around the paste distributor and over the brush, and also illustrating the normal position of the coating cutters.

Figure 4 is a sectional view taken approxi-

mately on the line 4—4 of Figure 3, looking in the direction of the arrows.

Figure 5 is a detail perspective view of the stationary cutter.

Figure 6 is a sectional view taken on the line 6—6 of Figure 1, looking downwardly, and

Figure 7 is a sectional view through the horizontal portion of the inverted U-shaped paste distributor.

In the drawings wherein for the purpose of illustration is shown the preferred embodiment of my invention, the numeral 1 designates a substantially U-shaped frame constructed of tubular material, and this frame is disposed horizontally. A vertically disposed hollow handle 2 is connected to the intermediate portion of the crown, or base of this U-shaped hollow frame by means of the T-fitting 3 so that the hollow handle will communicate with the tubular frame, for a purpose to be presently described.

As is clearly shown in Figure 1, this handle is slightly inclined.

A substantially inverted U-shaped tubular paste distributor unit 4 is formed at its free ends with the laterally disposed portions 5 that receive the free ends of the arms of the horizontally disposed tubular U-shaped frame 1 whereby said paste distributor unit is carried by the forward end of the frame 1 and formed in the crown portion of the U-shaped paste distributor 4 are the paste emitting apertures 6, the same being arranged in the particular manner as shown more clearly in Figure 7.

A pair of vertically disposed brackets 7 are secured at their lower ends to the intermediate portions of the respective arms of the U-shaped frame 1 and the upper end portion of the brackets are disposed forwardly and slightly upwardly for disposition above the inverted U-shaped paste distributor 4 as shown at 8 in Figures 1 and 3, respectively. Journalized for rotation between the free ends of the laterally disposed portions 8 are the pintles 9 that extend from the respective ends of the elongated rotary brush 10.

A roll of wall paper 11 is removably supported between the upper ends of the brack-

ets 12 that extend upwardly from the respective arms of the U-shaped frame 1 rearwardly of the brackets 7 and the free end of the wall paper extends forwardly between the brackets 7 over the cutting edge of the stationary transversely disposed cutter 13 that is formed at its respective ends with the laterally extending arms 14 for rigid attachment to the intermediate portions of the respective vertically disposed brackets 7, and said wall paper passes beneath the crown portion of the inverted U-shaped paste distributor unit 4, and thence upwardly over the rotary brush 10 as clearly shown in Figures 1 and 15 3 of the drawings. In Figure 5 there is shown the specific construction of the stationary cutter.

Cooperating with the stationary cutter is the movable cutter 15 that is disposed above the stationary cutter and is formed at its end with the rearwardly extending arms 16 that are pivotally connected at their free ends to the upper portion of the respective brackets 7 as at 17. A retractile coil spring 18 is connected at one end to one of the arms 16, and at its other end to the adjacent laterally disposed portion 8 for normally holding the pivoted cutter in a raised position out of engagement with the stationary cutter 13, and for the purpose of moving the pivoted cutter to an operative position, there is provided a lever 19 that is rigidly secured at its inner end to the forward end portion of each arm 16, and these levers extend forwardly beyond the inverted U-shaped paste distributor unit 4 outwardly of the respective arms thereof, as clearly indicated in Figures 1 and 2.

Journalized through suitable bearing members 20 that extend downwardly from the base portion of the U-shaped frame 1 adjacent the respective arms thereof is the elongated rod 21 and the outer ends of this rod have associated therewith the forwardly projecting arms 22 that are in turn connected to the outer ends of the respective levers 19 by means of the links 23.

An operating rod 23' is operatively connected at its upper end to the rock shaft forming rod 21 and this operating rod extends downwardly along the tubular handle 2 and has its lower end disposed through an offset guide 24 as shown more clearly in Figure 6. A handle 25 is arranged on the lower end of the operating rod as shown in Figure 1.

Also forming a salient part of the present invention is the paste receiving tank or receptacle 26 that is filled from the top and is provided with an outlet nipple 27 that has communication with the lower end of the hollow handle 2 through the medium of the flexible hose 28. A valve 29 is associated with the nipple 27, while a spring pressed valve 30 is associated with the lower end of the hollow handle 2.

An air pump 31 of any conventional con-

struction is operatively connected with the top of the tank 26 through the medium of the hose 32 and the piston rod 33 that is associated with the air pump 31 has at its upper end the handle 34 and manifestly when this piston is actuated, air under pressure is admitted to the tank 26 so that a pressure will be exerted on the paste. A gage 35 is associated with the top of the tank for indicating air pressure in said tank.

The operation of my improved wall paper hanging apparatus may be briefly stated as follows. The paper hanger holds the apparatus by the hollow handle 2, and by opening the valve 30 the paste under pressure will pass upwardly through the hollow handle and through the tubular frame into the tubular paste distributor unit from which said paste will be discharged through the openings 6 onto one face of the wall paper that is unrolled from the roll and the coated surface of the paper will be pasted to the ceiling or wall by the brush 10 in the manner as indicated in Figure 1, and as the apparatus is moved in the right hand direction, the paper will be unrolled from the roll, and coated and then pasted to the surface.

When the desired length has been unrolled, the handle 25 is actuated to operate the movable cutter 15 and bring the same into cooperation with the stationary cutter whereby to sever or cut the pasted strip from the roll, as is obvious from the construction shown in the drawings.

The cutting off of a length of wall paper from the roll is occasioned by swinging the operating rod 23' rearwardly in its offset guide 24 whereby to rock the rod or shaft 21 to effect the downward swinging movement of the forwardly projecting arms 22. This will result in the pivoted cutter being moved downwardly to an operative position for cooperation with the stationary cutter.

It will thus be seen from the foregoing description that I have provided a paper hanging apparatus that will expedite the papering of a wall or ceiling, and due to its simplicity the parts can be readily and easily actuated, and furthermore when the roll of wall paper has been entirely consumed, a new roll can be readily and easily placed in position on the frame.

Not only will an apparatus of this character save considerable time, but the same will enable a ceiling or any other overhead surface to be papered in an easy and efficient manner.

Furthermore a structure of the present character can be handled very easily. The device can also be manufactured at a very low cost and will be strong and durable and at all times positive and efficient in carrying out the purposes for which it is designed.

While I have shown the preferred embodiment of my invention, it is to be understood that minor changes in the size, shape

and arrangement of parts may be resorted to without departing from the spirit of the invention and the scope of the appended claims.

Having thus described the invention, what I claim is:—

5. 1. In a wall paper hanging apparatus, a tubular U-shaped frame adapted to support a roll of paper, a vertically disposed hollow handle communicating at its upper end with said tubular frame, a tank containing paste under pressure, means for delivering paste under pressure to the hollow handle, a substantially U-shaped tubular paste distributor unit communicating with the free ends of the arms of the U-shaped frame, the crown portion of the U-shaped paste distributor being formed with a series of paste emitting apertures, the free end of the strip of paper adapted to pass over the crown portion of the paste distributor unit, the paste being applied to one side of the paper as the same passes across the paste emitting aperture, and means supported by the frame for pasting the coated paper to a wall.

10 2. In a wall paper hanging apparatus, a tubular U-shaped frame adapted to support a roll of paper, a vertically disposed hollow handle communicating at its upper end with said tubular frame, a tank containing paste under pressure, means for delivering paste under pressure to the hollow handle, a substantially U-shaped tubular paste distributor unit communicating with the free ends of the arms of the U-shaped frame, the crown portion of the U-shaped paste distributor being formed with a series of paste emitting apertures, the free end of the strip of paper adapted to pass over the crown portion of the paste distributor unit, the paste being applied to one side of the paper as the same passes across the paste emitting aperture, and means supported by the frame for pasting the coated paper to a wall, means for cutting off a length of the coated wall paper from the roll, said last mentioned means comprising a stationary cutter supported on the frame transversely below the strip that is unrolled from said roll, and a pivoted coating cutter supported on the frame above said strip, means for normally holding the pivoted cutter in an inoperative position, and means operable adjacent the handle for moving the pivoted cutter to an operative position.

15 3. In a wall paper hanging apparatus, a tubular U-shaped frame adapted to support a roll of paper, a vertically disposed hollow handle communicating at its upper end with said tubular frame, a tank containing paste under pressure, means for delivering paste under pressure to the hollow handle, a substantially U-shaped tubular paste distributor unit communicating with the free ends of the arms of the U-shaped frame, the crown portion of the U-shaped paste distributor being formed with a series of paste emitting apertures, the free end of the strip of paper adapted to pass over the crown portion of the paste distributor unit, the paste being applied to one side of the paper as the same passes across the paste emitting aperture, and means supported by the frame for pasting the coated paper to a wall, said means comprising a pair of brackets extending upwardly from the arms of the U-shaped frame, the upper ends of the brackets being disposed laterally over the paste distributor unit, and a brush supported transversely between the free ends of the laterally disposed portions.

20 4. In a wall paper hanging apparatus, a tubular U-shaped frame adapted to support a roll of paper, a vertically disposed hollow handle communicating at its upper end with said tubular frame, a tank containing paste under pressure, means for delivering paste under pressure to the hollow handle, a substantially U-shaped tubular paste distributor unit communicating with the free ends of the arms of the U-shaped frame, the crown portion of the U-shaped paste distributor being formed with a series of paste emitting apertures, the free end of the strip of paper adapted to pass over the crown portion of the paste distributor unit, the paste being applied to one side of the paper as the same passes across the paste emitting aperture, and means supported by the frame for pasting the coated paper to a wall, means for cutting off a length of the coated wall paper from the roll, said last mentioned means comprising a stationary cutter supported on the frame transversely below the strip that is unrolled from said roll, and a pivoted coating cutter supported on the frame above said strip, means for normally holding the pivoted cutter in an inoperative position, and means operable adjacent the handle for moving the pivoted cutter to an operative position.

25 5. In a wall paper hanging apparatus, a tubular U-shaped frame adapted to support a roll of paper, a vertically disposed hollow handle communicating at its upper end with said tubular frame, a tank containing paste under pressure, means for delivering paste under pressure to the hollow handle, a substantially U-shaped tubular paste distributor unit communicating with the free ends of the arms of the U-shaped frame, the crown portion of the U-shaped paste distributor being formed with a series of paste emitting apertures, the free end of the strip of paper adapted to pass over the crown portion of the paste distributor unit, the paste being applied to one side of the paper as the same passes across the paste emitting aperture, and means supported by the frame for pasting the coated paper to a wall, said means comprising a pair of brackets extending upwardly from the arms of the U-shaped frame, the upper ends of the brackets being disposed laterally over the paste distributor unit, and a brush supported transversely between the free ends of the laterally disposed portions.

30 6. In a wall paper hanging apparatus, a tubular U-shaped frame adapted to support a roll of paper, a vertically disposed hollow handle communicating at its upper end with said tubular frame, a tank containing paste under pressure, means for delivering paste under pressure to the hollow handle, a substantially U-shaped tubular paste distributor unit communicating with the free ends of the arms of the U-shaped frame, the crown portion of the U-shaped paste distributor being formed with a series of paste emitting apertures, the free end of the strip of paper adapted to pass over the crown portion of the paste distributor unit, the paste being applied to one side of the paper as the same passes across the paste emitting aperture, and means supported by the frame for pasting the coated paper to a wall, said means comprising a pair of brackets extending upwardly from the arms of the U-shaped frame, the upper ends of the brackets being disposed laterally over the paste distributor unit, and a brush supported transversely between the free ends of the laterally disposed portions, and additional means for cutting off the coated por-
